Patented Sept. 3, 1912.

UNITED STATES PATENT OFFICE.

WILBUR G. PEET, OF BRIDGEPORT, CONNECTICUT, ASSIGNOR OF ONE-HALF TO THE KILPATRICK & HOTZ COMPANY, OF BRIDGEPORT, CONNECTICUT, A CORPORATION OF CONNECTICUT.

SOCKET-SWITCH.

1,037,304.

Specification of Letters Patent. Patented Sept. 3, 1912.

Application filed June 25, 1912. Serial No. 705,761.

To all whom it may concern:

Be it known that I, WILBUR G. PEET, a citizen of the United States, residing at Bridgeport, county of Fairfield, State of Connecticut, have invented an Improvement in Socket-Switches, of which the following is a specification.

This invention relates to electrical socket switches and has for its objects to simplify, 10 cheapen and to generally improve their construction and mode of operation.

With these objects in view I have devised the novel socket switch which I will now describe, referring to the accompanying drawing forming a part of this specification and using reference characters to indicate the several parts.

Figure 1 is a view partly in elevation and partly in vertical section illustrating the 20 construction of my novel switch; Fig. 2 a plan view of the lower insulating block and the switch mechanism, the brackets being in section and the returning spring removed; Fig. 3 a similar view with the operating 25 member and the hook removed; Fig. 4 an edge view of the operating member; Fig. 5 an inverted plan view of the operating member; Fig. 6 a perspective of the contact; Fig. 7 a perspective of the retainer; 30 Fig. 8 a plan view of the blade; Fig. 9 an end view corresponding with Fig. 8; Figs. 10, 11 and 12 plan views corresponding with Fig. 2, the contact and retainer and the returning spring being removed, showing different 35 positions of the parts in the operation of the switch, and Fig. 13 is a section on the line 13—13 in Fig. 8 looking in the direction of the arrows.

20 denotes the shell, 21 the cap, 22 the insulating lining, 23 the screw shell, 24 the upper insulating block, 25 the lower insulating block, 26 the operating chain and 27 the chain guide, all of which parts may be of any ordinary or preferred construction. 40 The insulating blocks are spaced apart and retained in operative position by current-carrying brackets 28 and 29, each of which carries a binding screw 31.

30 denotes a contact having electrical connection in any suitable manner with bracket 28. Bracket 29 is electrically connected to the screw shell by a screw 32 which passes through the lower insulating block and

rigidly secures both the screw shell and the bracket thereto.

Important features of my novel switch are an insulating operating member 33, an oscillating blade 34 and a blade retainer 35.

36 denotes the center screw with which the center contact of a lamp (not shown) 60 makes electrical connection. In the present instance I have shown the center screw as passing through the shank of the retainer and the several parts as retained in place by a nut 37. It is unimportant, however, 65 how the retainer is secured in place, as it is not in the circuit. The upper end of the center screw is unthreaded and forms a pivot on which the blade and the operating member oscillate. The blade is shown as 70 resting upon the nut and the insulating operating member as provided with a sleeve 38 which rests upon the blade. The operating member is actuated by means of a two-armed hook 39 to which the operating 75 chain is connected and is provided with shoulders 49, for a purpose presently to explained, and with shoulders 50 which engage the brackets (see Figs. 10 and 12) to limit the oscillation of said member in 80 either direction. A spring 40, one end of which is connected to the hook and the other to a stud or screw 41, acts to return the hook 85 to its normal position after each actuation. The operating member is provided on its upper side with pins 42 (shown in the present instance as connected and forming a yoke) which are adapted to be engaged by the arms of the hook respectively to actuate the switch (see Figs. 10, 11 and 12). Upon 90 the under side of the operating member is a two-armed spring 43 which is retained in place by a screw or stud 44 passing through the coil and the arms of which lie on opposite sides of sleeve 38 and engage the opposite sides of a pin 45 projecting from the blade. This pin is also engaged by shoulders 49 upon the operating member to disengage the blade from the contact and the retainer, as will be more fully explained. 95 The blade is preferably provided in its upper and under sides with grooves 46. The preferred form of the contact and retainer will be readily understood from Figs. 6 and 7, respectively, each being provided with 100 means for holding the blade. The contact is 105

shaped to secure as much contact surface as possible with the blade and is provided with a rib 47 which is adapted to engage the groove in the upper side of the blade to hold 5 the blade in engagement with the contact until it is disengaged therefrom by one of the shoulders on the operating member. The retainer is provided with a rib 48 which is adapted to engage the groove in the under 10 side of the blade and hold the blade in engagement with the retainer until it is disengaged by the other shoulder on the operating member.

The operation is briefly as follows: Starting 15 with the parts in the position shown in Figs. 2 and 10, in which the circuit is open and the blade is held by the retainer through the frictional engagement of the rib on the retainer with a groove in the blade, a pull 20 upon the chain will cause one of the arms of the hook to engage the pin 42 on the operating member toward the left in Fig. 10 and will move the parts to the position shown in Fig. 11, in which it will be seen that the 25 arms of spring 43 have been separated through movement of the operating member relative to pin 45 on the blade and the power of the spring is accumulating to throw the blade to the closing position as 30 soon as the engagement of a shoulder 49 on the operating member with the pin on the blade disengages the blade from the retainer and the full power of the spring acts to swing the blade to the position shown in Fig. 35 12 in which it is in engagement with the contact, the contact and retainer, however, being omitted from Figs. 10, 11 and 12 for the sake of clearness of illustration. The first pull upon the chain, therefore, closes the circuit. The instant the pull upon the chain is released, spring 40 returns the hook to its normal position, as in Fig. 12. A second pull 40 upon the chain will cause the other arm of the hook to engage the other pin 42 on the operating member and open the circuit again; that is, change the parts from the position shown in Fig. 12 to that shown in Fig. 10. The operation is precisely the same in opening or closing the circuit. The movement of 45 the operating member by means of the two-armed hook and chain accumulates power in one arm of the spring until the blade is disengaged by the shoulder on the operating member from either the contact or retainer, 50 as may be, after which disengagement the accumulated power of the spring quickly swings the blade from the closing to the opening position, or vice versa.

The passage of the current will be readily 60 understood from Fig. 18 in connection with the other views. Suppose bracket 29 to be the positive pole of the switch, the current would pass from said bracket to screw 82 and to the screw shell and returning 65 through the lamp (not shown) would pass

to the center screw, thence through the blade and contact to bracket 28.

Having thus described my invention I claim:

1. A switch of the character described, 70 comprising an oscillating blade, a contact and a retainer each provided with means for holding the blade, a spring acting to swing the blade into engagement with either contact or retainer and an operating member 75 acting on the spring to cause it to accumulate power and acting to disengage the blade from either contact or retainer, leaving the spring free to act.

2. A switch of the character described, 80 comprising an oscillating blade having grooves, a contact and a retainer, each having a rib adapted to engage one of the grooves for the purpose set forth, a spring 85 acting to throw the blade in either direction and an operating member acting to accumulate power in the spring and to disengage the blade from either contact or retainer.

3. A switch of the character described, 90 comprising an oscillating blade having a pin, a contact and a retainer each provided with means for holding the blade, an oscillating operating member having shoulders adapted to engage the pin and disengage the 95 blade and a spring acting to throw the blade into engagement with the contact when disengaged from the retainer and vice versa.

4. A switch of the character described, 100 comprising an oscillating blade, a contact and a retainer each provided with means for holding the blade, an oscillating operating member adapted to disengage the blade from either contact or retainer and a spring acting to throw the blade into engagement with either contact or retainer when disengaged 105 from the other.

5. A switch of the character described, 110 comprising an oscillating blade, a contact and a retainer each provided with means for holding the blade, an oscillating operating member adapted to disengage the blade from either contact or retainer and a spring carried by the operating member and engaging the blade, substantially as described 115 for the purpose specified.

6. A switch of the character described, 120 comprising an oscillating blade, a contact and a retainer each provided with means for holding the blade, an oscillating operating member adapted to disengage the blade from either contact or retainer, a spring carried by the operating member and engaging the blade for the purpose set forth and chain operated means for actuating the operating member.

7. A switch of the character described, 125 comprising an oscillating blade, a contact and a retainer each provided with means for holding the blade, an oscillating operat- 130

ing member adapted to disengage the blade from either contact or retainer, a spring acting to throw the blade into engagement with either contact or retainer when disengaged from the other, a two-armed hook adapted to actuate the operating member and means for actuating the hook and for returning it to its normal position.

8. A switch of the character described, comprising an oscillating blade, a contact and a retainer each provided with means for holding the blade, an oscillating operating member adapted to disengage the blade from either contact or retainer and provided with pins, a spring acting to throw the blade into engagement with either contact or retainer when disengaged from the other, a two-armed hook adapted to engage either

pin to actuate the operating member and means for actuating the hook and for returning it to its normal position.

9. A switch of the character described, comprising an oscillating blade, having a pin, a contact and a retainer each provided with means for holding the blade, an oscillating operating member having shoulders adapted to engage the pin, for the purpose set forth, and a spring acting to swing the blade in either direction.

In testimony whereof I affix my signature in presence of two witnesses.

WILBUR G. PEET.
